CLAIM

The ornamental design for a scrunchie-style headphone or headset for an electronic device, as shown and described.

DESCRIPTION

FIG. 1 is a front elevated perspective view of a scrunchie-style headphone or headset for an electronic device, showing the new design;

FIG. 2 is a front view thereof;

FIG. 3 is a rear view thereof;

FIG. 4 is a side view thereof;

FIG. 5 is the opposite side view thereof;

FIG. 6 is a top view thereof; and,

FIG. 7 is a bottom view thereof.

The broken lines shown are included for the purpose of illustrating portions of the scrunchie style headphone or headset for electronic device that form no part of the claim.

1 Claim, 7 Drawing Sheets
